[57] CLAIM

An ornamental design for an ice scraping comb, as shown.

DESCRIPTION

FIG. 1 is a front perspective view of the ice scraping comb of the present invention;

FIG. 2 is an end view thereof;

FIG. 3 is a top view thereof; and,

FIG. 4 is a front view thereof.

The rear, bottom and the end opposite that shown in FIG. 2 of the article neither shown in the drawing nor described in the specification form no part of the claimed design.
